(57) **CLAIM**

The ornamental design for a jet body for use with grommets, as shown and described.

DESCRIPTION

FIG. 1 is a side perspective view of a first embodiment showing the new design for a jet body for use with grommets.

FIG. 2 is a front view of the first embodiment thereof.

FIG. 3 is a rear view of the first embodiment thereof.

FIG. 4 is a right side view of the first embodiment thereof.

FIG. 5 is a left side view of the first embodiment thereof.

FIG. 6 is a top view of the first embodiment thereof.

FIG. 7 is a bottom view of the first embodiment thereof.

FIG. 8 is a side perspective view of a second embodiment thereof.

FIG. 9 is a front view of the second embodiment thereof.

FIG. 10 is a rear view of the second embodiment thereof.

FIG. 11 is a right side view of the second embodiment thereof.

FIG. 12 is a left side view of the second embodiment thereof.

FIG. 13 is a top view of the second embodiment thereof; and,

FIG. 14 is a bottom view of the second embodiment thereof.

The broken line showing is included for the purpose of illustrating portions of the article and forms no part of the claimed design.
